UNITED STATES PATENT OFFICE

152,603

DESIGN FOR A PLAITED SKIRT

Ernest Donath, Brookline, Mass.

Application September 14, 1948, Serial No. 148,581

Term of patent 7 years

(Cl. D3—26)

To all whom it may concern:

Be it known that I, Ernest Donath, a citizen of the United States of America, residing at Brookline, in the county of Norfolk and Commonwealth of Massachusetts, have invented a new, original, and ornamental Design for Plaited Skirt, of which the following is a specification, reference being had to the accompanying drawing, forming part thereof.

Fig. 1 is a front view of a plaited skirt, showing my new design;

Fig. 2 is a rear view of the skirt;

Fig. 3 is an enlarged section on line 3—3 of Fig. 1; and

Fig. 4 is an enlarged section on line 4—4 of Fig. 1.

I claim:

The ornamental design for a plaited skirt, as shown.

ERNEST DONATH.
